Primary Examiner—Stacia Cadmus

(57) **CLAIM**

The ornamental design for a wheel, as shown and described.

DESCRIPTION

FIG. 1 is a perspective view of the wheel of our new design; FIG. 2 is a front elevational view thereof; FIG. 3 is a rear elevational view thereof; and, FIG. 4 is a side elevational view thereof, the opposite side elevational view being a mirror image thereof. The top and bottom plan views are identical to FIG. 4.
